UNITED STATES PATENT OFFICE

135,979

DESIGN FOR A TIRE BRANDING IRON

Don C. Weyl, Wichita, Kans.

Application May 11, 1942, Serial No. 106,863

Term of patent 3½ years

To all whom it may concern:

Be it known that I, Don C. Weyl, a citizen of the United States, residing at Wichita, in the county of Sedgwick and State of Kansas, have invented a new, original, and ornamental Design for a Tire Branding Iron, of which the following is a specification, reference being had to the accompanying drawing forming a part thereof.

Fig. 1 is a perspective view of the tire branding iron, showing my new design.

Fig. 2 is a top plan view thereof.

Fig. 3 is a front elevational view thereof.
Fig. 4 is an elevational view of one end thereof; and

Fig. 5 is an elevational view of the opposite end thereof.

The handle has been omitted from Figs. 2, 4 and 5 for convenience of illustration.

I claim:

The ornamental design for a tire branding iron, as shown and described.

DON C. WEYL.
